J. C. FERRY.
HIP POCKET FOR MEN'S TROUSERS.
APPLICATION FILED MAY 24, 1912.

1,108,352.

Patented Aug. 25, 1914.

UNITED STATES PATENT OFFICE.

JOHN CHRISTOPHER FERRY, OF SYDNEY, NEW SOUTH WALES, AUSTRALIA.

HIP-POCKET FOR MEN'S TROUSERS.

1,108,352.

Specification of Letters Patent. Patented Aug. 25, 1914.

Application filed May 24, 1912. Serial No. 699,606.

To all whom it may concern:

Be it known that I, JOHN CHRISTOPHER FERRY, a subject of the King of Great Britain, residing at Leichhardt, Sydney, New 5 South Wales, Australia, have invented certain new and useful Improvements in Hip-Pockets for Men's Trousers, of which the following is a specification.

My invention has for its object to provide a hip-pocket for men's and youths' 10 trousers, breeches, knickers and such like garments, which shall be handier to the reach, neater in appearance, and safer in any position of the wearer, or from picking 15 pockets, than the ordinary hip-pocket now in use, and which will be practically a secret pocket, there being no outward evidence of its existence.

The novel features of the invention will 20 be apparent from the following description taken in connection with the accompanying drawings.

In the drawings: Figure 1 is a section of 25 the side of a pair of trousers showing the position of the pocket A which is the subject of the invention, and its position in relation to the remainder of the garment. Fig. 2 is a fragmentary view, showing the bearer or flap pulled out and back, to allow 30 the hand free access to the hip-pocket. Fig. 3 is a horizontal section showing the mouth of hip-pocket again closed, by flap being returned to original position. Fig. 4 illustrates a modification of my invention, in 35 which inverted curved edges are used, and showing the flap reduced.

According to this invention there is no entrance to the hip pocket except through the vertical side opening at the side seam 40 of the trousers which affords access to the ordinary side pocket. When the trousers are on the wearer the side pocket extends around his body forwardly from the entrance at the side seam, whereas the hip 45 pocket extends around the body to the rear of said entrance. The mouth of the hip pocket is within the mouth of the side pocket so that in using the hip pocket the wearer must thrust his hand forward into 50 the mouth of the side pocket and then turn it back into the concealed entrance to the hip pocket.

In the drawings O represents the side 55 seam of a pair of trousers made up of the front section X and the rear section R. The usual side pocket opening D is formed

at the side seam, the material of the front section X along this opening being cut on a decided curve as shown in Figs. 1, 2 and 4 so that the material will project rearwardly 60 over the mouth of the pocket. The outer wall of the side pocket B is seamed to the inner face of the material on the curved edge along the opening D. The outer wall of the hip pocket A is seamed to the inner 65 edge of the rear section material R on a line with the side seam O. The material of the section R along the side pocket opening is cut on a decided curve forming a flap C which projects forwardly of the side seam. 70 This flap is loose and free forwardly of the vertical line of stitches above mentioned securing the outer wall of the hip pocket to the material. This flap may lie within the side pocket, as shown in Fig. 1, or be pulled 75 out to the position shown in Fig. 2. The rear wall of the side pocket is seamed at its rear edge to the front edge of the rear wall of the hip pocket, thus forming an opening E for affording an entrance to the hip 80 pocket.

It will be observed that the walls of the side pocket B lie against and parallel to the front section X extending forward from the side seam and that the walls of the hip 85 pocket B lie along and parallel to the section R extending to the rear. The flap C in normal position is shown in full lines in Fig. 3 lying over the opening E for the hip pocket so that a hand inserted through 90 opening D would be guided forward into the side pocket B and would feel no noticeable indication of the pocket A. The flap C, however, can be pulled out by the wearer to the position shown in dotted lines in Fig. 95 3, and the hand can then be passed through the opening D and back through the opening E into the hip pocket A.

It will be observed that the hip pocket is concealed and that pickpockets cannot 100 easily get access to it. The construction, furthermore, is such as to prevent accidental loss of things from the pocket when the wearer is in any position.

In Fig. 4 I have shown a construction in 105 which instead of making use of the loose flap C covering the opening E of the hip pocket I cut the edge H of the material R on a curve projecting forward within the pocket opening D and seam the outer wall 110 of the hip pocket to that edge. The opening E is then protected by this inwardly

projecting material and the hand cannot by accident get into the hip pocket when thrust through the opening D.

Having thus described the invention what is claimed is:

In a device of the class described, the combination with a garment having a substantially vertical pocket opening, of two pockets leading downward therefrom in different directions, and a loose flap secured

along the edge of said opening and adapted to extend into one pocket across the entrance to the other pocket.

In testimony whereof I affix my signature in presence of two witnesses.

JOHN CHRISTOPHER FERRY.

Witnesses:

JOHN P. BRAY,
H. C. CAMPBELL.
